(57) **CLAIM**

The ornamental design for a hand switch for medical radiography, as shown and described.

DESCRIPTION

FIG. 1 is a perspective view of a hand switch for medical radiography;

FIG. 2 is a front view of the hand switch for medical radiography of FIG. 1;

FIG. 3 is a rear view of the hand switch for medical radiography of FIG. 1;

FIG. 4 is a left-side view of the hand switch for medical radiography of FIG. 1;

FIG. 5 is right-side view of the hand switch for medical radiography of FIG. 1;

FIG. 6 is a top plan view of the hand switch for medical radiography of FIG. 1; and,

FIG. 7 is a bottom plan view of the hand switch for medical radiography of FIG. 1.
